UNITED STATES PATENT OFFICE.

NELSON J. WARREN AND ARTHUR J. FIELD, OF WAGNER, SOUTH DAKOTA.

LIQUID-DISPENSING APPARATUS.

1,408,552.

Specification of Letters Patent. Patented Mar. 7, 1922.

Application filed February 16, 1920. Serial No. 359,193.

To all whom it may concern:

Be it known that we, NELSON J. WARREN and ARTHUR J. FIELD, citizens of the United States, and residents of Wagner, in the county of Charles Mix and State of South Dakota, have invented certain new and useful Improvements in Liquid-Dispensing Apparatus, of which the following is a specification.

10 Our present invention has for its primary object the production of an improved liquid dispensing apparatus particularly adapted for dispensing gasoline.

Another object of the invention is the production of a gasoline dispensing apparatus or motor-vehicle filling-station, embodying a plurality of gasoline containers, and so constructed and associated that while one container is being drained another is being filled.

Furthermore the invention contemplates a gasoline filling-station embodying a plurality of gasoline containers, quantity-indicating means for the respective containers and valve mechanism constructed and arranged that while a container is being drained, an empty container is being filled.

Still a further object of the invention is the production of a gasoline filling station comparatively simple and inexpensive in construction, yet durable, dependable and thoroughly efficient in operation.

These and other objects we successfully attain in the embodiment hereinafter described, defined in the appended claims and illustrated in the accompanying drawings, which form a part of this application and in which like characters of reference indicate corresponding parts throughout the

40 several views, of which,—

Fig. 1 is a front elevation of a device constructed in accordance with the invention, parts thereof being cut away to reveal the internal characteristics;

45 Fig. 2 is a central vertical section thereof taken at right angles to Fig. 1;

Fig. 3 is a horizontal section taken on the line 3—3 of Fig. 1;

50 Fig. 4 is an enlarged inverted horizontal section taken on the line 4—4 of Fig. 1;

Fig. 5 is an enlarged front elevation of the outlet valves and associated parts;

Fig. 6 is a plan of one of the valve connecting links and associated parts shown fragmentarily; and

55

Fig. 7 is a side elevation thereof.

While we have illustrated and hereinafter described the preferred embodiment of the invention, we would not be understood as being limited to such specific construction, for various alterations and modifications may be made in the details of construction and arrangement of the parts described, without departing from the spirit and scope of the invention, as defined in the appended claims.

Referring, now, to the illustrations, the device consists, preferably, of a cylindrical jacket of upper and lower parts, 8 and 9 respectively, the part, 9, being mounted on a suitable support, as a base ring, 10, having a flange, 11, which is encircled by the jacket portion, 9. Upon the upper end of the jacket portion, 9, rests a plate, 12, having an annular flange, 13, engaging the inner periphery of the jacket portion 9. Upon the plate, 12, rests the jacket portion, 8, held in axial alinement with the lower jacket portion by a flange, 14, on the plate, 12. The jacket is covered by a dome, 15, having a flange, 16, encircled by the jacket, and formed with inner lugs, 17, through which pass tie-rods, 18, which depend through the plate, 12, and are suitably secured as at 19, to the base ring to securely fix the jacket, its cover, plate 12, and base 10, against relative movement.

The jacket portion, 8, encloses two containers or tanks, 20 and 21, supported side by side upon the plate, 12. The front of the jacket portion, 8, is provided with an opening, 22, enclosing an upright strip, 23, having grooves, 24, enclosing gauge glasses, 25, the lower ends of which communicate with the respective tanks through suitable ducts, 26; and the face of the strip, 23, between the grooves is graduated as at 27, in suitable units of liquid measure. Within the gauge glasses, 25, are floats, 28, preferably bright colored, rendering them readily visible. Thus, the gasoline maintains the same level in the gauges as in the tanks, and the quantity of gasoline in either tank is readily determined by the position of the

70

100

associated float with respect to the adjacent scale, 27.

The bottom of each of the tanks, 20 and 21, is provided with a suitable inlet valve, 30, and an outlet valve, 31. The inlet valves of the two tanks are interconnected by a manifold or pipe, 32, with a pipe, 33, adapted to be connected with a suitable source of gasoline pressure; and the valves, 31, are 10 similarly interconnected by a manifold or pipe, 34, with an outlet pipe, 35, communicating with a flexible duct or hose, 36, extending through an opening, 37, in the jacket portion, 9. The valves are provided with 15 horizontally oscillating controlling arms, 38, which normally are rearwardly swung as shown in full lines in Fig. 4.

When the valves are closed the valves, 30, are held yieldably closed as by retracting 20 springs, 39, secured to the arms, 38, and the jacket, 9, and the valves, 31, may be held yieldably closed as by retracting springs, 40, secured to controlling arms, 38, and the tank-supporting member, 12.

25 To the outlet-valve controlling-arms, 38, we secure rods, 41, respectively, the free ends of which protrude through openings, 42, in jacket portion, 9, and are provided with suitable handles, 43, for pulling the 30 rods outwardly or forwardly. The inlet-valve controlling-arm of each tank and the outlet-valve controlling-arm of the companion tank are so connected that they are opened in unison and permitted to close, each 35 independently, from the other, whereby one tank, if empty or partially empty, will be filling while the other is being drained, and when the one is properly filled, means are provided for automatically closing its inlet- 40 valve while the other tank may still be draining. For this purpose we interconnect the inlet-valve controlling-arm of each tank with the outlet-valve controlling-arm of the other tank by a rod or other suitable 45 link, 44. The induction-valve controlling-arms are provided with swivel heads, 45, through which pass reduced portions, 46, of the associated rods, 44, provided on their rear ends with bosses, 47, engageable with 50 the heads, 45, to swing the adjacent valve-controlling-arms forwardly, as presently will appear. The said rods are held yieldably rearwardly as by retracting springs, 48, secured to the rods and the jacket portion, 9. The eduction-valve-controlling-arms, 38, are provided with suitable heads, 49, having slots, 50, in which the associated rods, 44, are free to slide. In the underside 55 of the arms, 44, are notches, 51, which normally so engage the heads, 49, that when the rods, 44, are drawn forwardly, similar motion is imparted to the associated controlling arms, 38.

Now, it will be observed, when one of the 60 rods, 41, is drawn forwardly the outlet-valve

controlling-arm, 38, therewith connected, and the associated inlet-valve controlling-arm will both be drawn forwardly to open their valves.

The inlet-valves are held open when their controlling-arms are swung forwardly by means of float-controlled latch mechanism, which includes horizontal arms, 52, which intersect the sweep of the said controlling arms and have one end pivoted to suitable 70 bearings, 53, mounted on the supporting element, 12, and their free ends are pivoted to the lower ends of rods, 54, the opposite ends of which are pivoted to the intermediate portions of arms, 55, having one end pivoted 75 to suitable bearings, 56, on the superstructure and carrying at their free ends depending rods, 57, provided with floats, 58, within the respective tanks. The undersides of the arms, 52, are provided with notches, 59, engageable with lugs, 60, on the inlet-valve controlling-arms, 38. Now, when one of the rods, 44, is moved forwardly, the associated 80 induction-valve is held open by virtue of engagement of the notch, 59, in the adjacent 85 latch arm, 52, with the lug, 60, and as the rod, 44, approaches its extreme forward position it engages a shoulder, 61, on the interior of the jacket, whereby the notched portion, 51, thereof is disengaged from the 90 slotted head, 49, which permits the spring, 48, to retract and leave both valves open; then when the desired quantity of gasoline is drained from the tank the controlling rod, 41, is released permitting the eduction-valve 95 controlling-arm to swing rearwardly and close its valve; and as the float is raised by gasoline in the tank being filled, the latch arm, 52, is lifted through the medium of the associated rod, 54, to disengage the notched 100 portion, 59, from the lug, 60, whereupon the induction valve immediately closes.

Having thus described our invention, what we claim as new and desire to secure by Letters Patent of the United States is,—

1. A liquid-dispenser embodying a plurality of liquid containers, induction and eduction valves for each container, each valve including movable controlling means, connections between the eduction valve-controlling means of each container and the induction valve-controlling means of another container operable to open the connected valves simultaneously, and permit them to be closed independently, each from the other, 115 and float-controlled means operable to automatically close the induction valves.

2. A liquid-dispenser embodying a pair of uniform liquid containers, induction and eduction valves for each container, each 120 valve including movable controlling means, a connection between the induction-valve controlling means of each container and the eduction-valve controlling means of the other container operable to open the con- 125 130 135

ected valves simultaneously and permit them to be closed independently, each from the other, yieldable means for retracting the induction-valve controlling means, floats in the containers, and latches governed by the respective floats for releasably engaging the induction-valve controlling means of the

associated containers to hold their valves open.

In testimony whereof we have hereunto set our hands this 18th day of Nov., 1919.

NELSON J. WARREN.
ARTHUR J. FIELD.
